UNITED STATES PATENT OFFICE

2,351,723

FIN MAST ANTENNA

Arthur G. Vogel, Chicago, Ill., assignor to Rempe Company, Chicago, Ill., a corporation of Illinois

Application May 22, 1943, Serial No. 487,996

1 Claim. (Cl. 250—33)

My invention relates to mast antennas for radio reception. Its object is to improve radio reception, especially with the type of mast antenna which is directionally adjustable. The improvement in reception is achieved by my invention without increasing the length of the mast antenna and without increasing the transverse dimensions thereof to an extent appreciably to complicate packaging it, or to interfere with its juxtaposing a wall which it may parallel.

Also, by my invention I may laterally extend the surface as a multiplicity of surfaces in condenser-like relationship and at normals to the axis of the mast, which extended surface is rather compactly arranged about the mast and rigidly fixed thereon and supported thereby.

My invention also concerns an improved insulated mounting and adjustable bracketing of the antenna mast.

The foregoing, together with further objects, features, and advantages of my invention, are set forth in the following description of a specific embodiment thereof as illustrated in the accompanying drawing wherein:

Fig. 1 is a perspective view of the fin mast antenna of my invention mounted on a window frame; and

Fig. 2 is a longitudinal vertical section thereof.

My fin mast antenna 10, as a whole, is shown as mounted on the exterior frame 11 of a window and preferably swung and inclined somewhat upwardly of a direction toward the transmitting station from which reception is most sought. The backbone or mast proper of my antenna is a tube 12 of high conductivity metal preferably of uniform external diameter. Upon this tube are rigidly mounted, at spaced intervals, a multiplicity of fins 13. While these fins may be discs, I prefer that they be squares of thin sheet stock of a high conductivity metal such as copper.

Each fin 13 has a central hole 14 whereby the fins can be slipped upon the tube. The central hole 14 of each fin may be margined by a narrow flange 15 making surface contact with the periphery of the tube.

The fins are made fast upon the tube in any well-known manner such as by internal expansion of the tube, by crimping the flange 15 upon the tube, by making the hold 14 such a tight fit that the fins are adequately fixed by friction, by welding, or by a metal bath.

Whatever be the specific technique employed for fixing the fins, they are made sufficiently fast to preserve them, under ordinary treatment, at normals to the axis of the mast whereby each

fin is maintained substantially parallel with its neighboring fins.

I have found that, balancing cost and weight against performance, it is most desirable that the inter-fin spacing be in the order of about half the fin width, and that the fin width be several times the tube diameter.

The upper end of the tube may be closed by a pointed plug 16 preferably of metal.

10 The lower end of the tube 12 is fitted into the socket 17a of a piece of insulation 17, and is fixed therein as by cementing. The piece of insulation 17 also preferably embodies a convex dished shield 17b, the margins of which are undercut to shed water.

15 The bottom end of the piece of insulation 17 is conformed as a threaded stud 17c. The socket 17a preferably extends, as shown, well down into the interior of the threaded stud 17c, whereby the metal tube 12 serves to reinforce the insulation piece at the neck of the stud 17c where the piece of insulation would otherwise be most likely to break.

20 The stud 17c threads into the socket 18 of the ball member 19 of a mast mounting which also includes a complementary or socket member 20 fixed to the window frame or other supporting surface as by wood screws 21. The ball and socket members 19 and 20, which may be of 25 metal, permit a universal direction adjustment of the mast antenna, which adjustment may be fixed by socket clamping thumb screws 22.

25 The lead-in conductor 23 may conveniently be connected to the base of the tubes or, as here shown, to the lowermost fin.

30 My fin mast antenna is disposed with its axis in a more or less vertical position and consequently the several fins are in more or less horizontal position and thereby in turn more or less parallel with the ground, tending toward increasing the condenser capacity of the antenna in its radio reception.

35 By the compactly arranged surface extension at normals to the axis of my antenna its condenser capacity is greatly increased for the improvement of radio reception, without increasing its over-all length and without substantially increasing the over-all transverse dimensions of the antenna beyond those of the usual shield and mounting.

I claim:

40 A mast antenna for radio reception comprising a supporting means adapted to be secured to a building or other supporting structure including a pair of metallic members one of which is adapt-

ed for rigid securement to said structure, the other member being adjustably secured to the first member adjacent one of its ends, and being provided with a socket on its other end, an insulator provided with a stud member, means on said stud member and socket for securing them together, said insulator having an elongated socket, a one-part mast comprising an elongated metallic tubular member, one end of which is adapted to fit within said elongated socket, and a multiplicity of plates, each plate being comprised of a material of high electrical conductivity, means

on said plates for mounting said plates in spaced relation directly on said mast comprising an aperture in each plate having a margin defined by a flange, said flange making low impedance surface contact with said mast and means for fixedly mounting said flange on said mast whereby said tubular mast forms the sole support for said plates, said mast and plates constituting the effective antenna, and a lead-in conductor connected to said effective antenna.

ARTHUR G. VOGEL.
